(57) **CLAIM**

We claim, the ornamental design for a combined micro valve and pressing member for controlling path of fluids in miniaturized capillary connections, as shown and described.

DESCRIPTION

FIG. 1 is a perspective view of a combined micro valve and pressing member for controlling path of fluids in miniaturized capillary connections showing our new design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines indicate the bounds of the claim and form no part of the claimed design.
